CLAIM

The ornamental design for a golf ball holder, as shown and described.

DESCRIPTION

FIG. 1 is a perspective view of a golf ball holder showing my new design;

FIG. 2 is a front elevational view of the golf ball holder;
FIG. 3 is a rear elevational view of the golf ball holder;
FIG. 4 is a side elevational view of the golf ball holder;
FIG. 5 is a side elevational view of the golf ball holder;
FIG. 6 is a top plan view of the golf ball holder; and,
FIG. 7 is a bottom plan view of the golf ball holder.
The broken lines showing golf balls, golf tees, and a marker are illustrative of environmental structure only and form no part of the claimed design.
